FILLING HEAD FOR CAN FILLING
MACHINES

James Leonard, Rochester, N. Y.

Application January 11, 1930. Serial No. 420,248

3 Claims. (Cl. 226—122)

This invention relates to filling heads for can filling machines that are used for filling semi-solids such as tomato sauce etc. for saucing spaghetti, beans, etc., and the object of this invention is to provide a filling head with which the cans can be filled without loss of material after each filling operation.

This and other objects of this invention will be fully illustrated in the drawing, described in the specification and pointed out in the claims at the end thereof.

In the accompanying drawing:

Figure 1 is a vertical sectional view of the filling head, the section being taken on the line 1x—1x of Figure 2.

Figure 2 is a bottom plan view of the filling head.

Figure 3 is a side elevation of the filling head with a portion partly broken away at the top.

In the several figures of the drawing, like reference numerals indicate like parts.

The filling head forming the subject matter of my present invention is especially adapted for use in filling cans with semi-solid canned material such as tomato sauce or any other similar material used for saucing spaghetti, etc. Such material has been found to be very difficult to fill into cans by machinery because of the semi-solid state in which the material although free flowing, has to be handled. Can filling machines, used for this purpose have, therefore, been found to be very inefficient in the handling of these canned goods. Much of the trouble in filling cans with the semi-solid material is due to the fact that the material is retained in the intake and air passage of the filling head of the machine allowing this retained material to drip from the filling head after the filled can has been withdrawn.

The cans are filled by the can filling machine by means of gravity in which the material is fed from a tank located above the head into the can to be filled. To make this possible, the air from the can is allowed to escape thru an air line in the filling head. This air line also fills up with canning material in present day machines because of the excess of semi-solid matter allowed to feed into the can so that the material in the air line drips from the filling head after the filled can has been withdrawn. In the type of filling head forming the subject matter of this invention the retaining of any semi-solid matter in the filling or supply line or the air line has been practically eliminated, and the filling head operates in such a manner that none of the material is lost during the filling operation by dripping from the filling head before a can is located under it.

As illustrated in the figures of the drawing, the filling head comprises a solid center 1 having a disc web 2 surrounding it centrally thereof. At the bottom, this solid center is threaded as indicated at 3. Surrounding the solid center is a housing 4 which is shaped with an annular channel which is provided with a resilient rubber gasket or seal 5 which is mounted therein and is concentric with the solid center. An annular rim 6 extends upward from the housing and surrounds the web 2. The housing 4 with its rubber packing, has a threaded engagement with the solid center and is adjustable up and down thereon by merely turning it. The rim of the annular casing is perforated at intervals as indicated at 7 to 70 which perforations a wrench can be applied for the purpose of turning it. These perforations also permit drainage of any water that may become trapped between the web 2 and the annular casing 4 in the washing of the apparatus. The rubber gasket 5 fits down upon the can 8 that is being filled and makes an air tight joint therewith.

The filling line, the air line through which the air escapes during the filling operation and the vacuum relief or vent all extend through the solid center 1 and in each of them is located a valve by means of which the opening through the solid center is controlled. The filling line is indicated at 8a and this has the largest inside diameter and through this is drawn the matter that is filled into the can, which matter is semi-solid and yet is free flowing. The lower end of this filling line is enlarged as indicated at 9 and between the filling line and the enlarged end is formed the valve seat 10. Cooperating with this valve seat is the piston valve 11 which moves in the enlarged end 9 of the filling line and is carried on the lower end of the valve stem 12. The enlarged end 9 of the filling line and the filling line itself is cylindrical throughout while the piston valve 11 has three ribs 13 thereon as shown in Figure 2.

The valve stem 12 extends through the filling line and up through the tank 14 which rests on the flange 15 formed above the solid center. The valve stem carries on its upper end suitable means whereby the valve may be raised and lowered to open and close the valve 11 on the seat 10. The valve 11 practically completely fills the enlarged end of the filling line so that none of the semi-solid material can pass through the liquid line 105 and enter the can 8 placed below the filling head except through the filling line 8a. As the valve 11 is unseated the semi-solid material flows through the filling line 8a past the valve 11 and into the can 8 below the filling head. The ma-

aterial is allowed to flow from the tank 14 into the can 8 in this manner until it is filled. As the can is filled the air within the can escapes through the air line 16 which air line is controlled by a valve 17 which is similar to the valve 11 and which is mounted upon the stem 18 by which it is raised and lowered to control the opening and closing of the air line. The valve 17 is adapted to seat itself upon the seat 19. The enlarged lower end 20 of the air line 16 is cylindrical as is the upper part of the air line at 16. The air valve 17 is provided with ribs 21 between which the air can escape.

These ribs are on the valves 11 and 17 to prevent any of the solid matter that is in the can from backing up through the filling line or the air line and clogging the lines. It will be understood that the cans are filled first with beans, peaches or other similar matter before they come to this machine and the filling of the cans is then finished on this machine by adding the sauce or syrup etc. to the cans. The ribs on the valves 11 and 17 prevent any of the solid matter in the cans from finding its way up into the valve seat or into the line above in which case it would interfere with the operation of the filling head.

A vent 22 is also provided in the solid head which is normally closed by a cone shaped valve 23 which is used for a purpose that will now be described.

On machines of this character the can is held in place under the filling head by a small platform that raises and lowers as the machine rotates. This platform raises the can in place against the filling head and holds it there during the filling operation. After the filling is completed and the valves 11 and 17 are closed this platform drops and carries the can with it away from the filling head. If however, a partial vacuum has been established in the can, the can will adhere to the filling head. This vacuum is always destroyed by pushing down on the valve 23 for which purpose a lever 24 is provided pivoted at 25, the outer end of which lever is pushed down in any suitable manner. This raises the valve 23 and admits air into the can destroying the vacuum so that the can falls away from the filling head by gravity.

The threaded engagement between the solid center and the annular casing 4 permits the rubber gasket 5 to move up or down and this in turn permits accurate gauging of the height to which the material is filled into the can. As shown in Figure 1, the annular casing 4 is at its highest point. By turning it around it can be brought down on the solid center and the further down

it is drawn on the solid center, the more it will cause the can to be filled. That is, it will cause the can to be filled closer to the top. The higher the annular casing 4 is placed on the solid center, the more unfilled space will be left at the top of the can when the filling operation has been ended. On the rim 6 at the top is provided a slot 26 at frequent intervals. A dog 27 is provided to engage one of these slots. When the annular casing 4 has been fixed at the correct height, the dog will engage one of the slots and lock the casing so as to hold it in that position, thus securing uniformity in the filling of the can.

In the operation of my filler head the can is brought into contact with the gasket 5 and the valve 17 is then pushed down. This allows any material in the air vent to drain into the can. Then the valve 11 is pushed down and the material in the filling line then flows down into the can and as it flows in to the can, the air flows out through the air line 16. As soon as the can is filled, the valves 11 and 17 both close and then the valve 23 opens permitting the can to drop away from the gasket, as the platform that supports it drops away.

I claim:

1. A filling head comprising a solid center, having an air line and liquid filling line therein, a housing threaded on said center, said housing being channel shaped and holding a packing 105 therein adapted to engage with the rim of a can, said housing being adjustable up and down on the center by turning it thereon, said center having a web extending radially therefrom, said housing having a cylindrical flange extending upwardly therefrom and engaging with and being guided by the rim of said web.

2. A filling head comprising a solid center, having an air line and liquid filling line therein, a housing threaded on said center, said housing 115 being channel shaped and holding a packing therein adapted to engage with the rim of a can, said housing being adjustable up and down on the center by turning it thereon, notches formed in the upper rim of the housing, a latch pivoted 120 on the solid center, adapted to engage with any one of said notches, placed in line therewith.

3. A filling head comprising a solid center, having an air line and liquid filling line therein, valves at the bottom of said lines, valve stems 125 extending up through said lines from said valves, each of said valves having a cone at the upper end thereof and a cylindrical body, extending down therefrom with ribs thereon extending along the body.

JAMES LEONARD.
